UNITED STATES PATENT OFFICE.

ERNEST E. SUTHERLAND, OF MANSFIELD, OHIO, ASSIGNOR TO WESTINGHOUSE ELECTRIC & MANUFACTURING COMPANY, A CORPORATION OF PENNSYLVANIA.

ELECTRIC RESISTOR SUPPORT.

Application filed April 21, 1924. Serial No. 707,814.

To all whom it may concern:

Be it known that I, ERNEST E. SUTHERLAND, a citizen of the United States, and a resident of Mansfield, in the county of Rich-
5 land and State of Ohio, have invented a new and useful Improvement in Electric Resistor Supports, of which the following is a specification.

My invention relates to electric heating
10 units and particularly to supports for helical resistor members.

The object of my invention is to provide a simple and practical electric heating unit that is easily assembled and is rugged in
15 construction.

In practicing my invention, I provide a refractory plate of electrically insulating material. A plurality of spiral grooves are provided in the upper surface of the plate, each having side walls that are angularly disposed to each other. Bridging members integral with the walls of the grooves extend laterally therebetween and are provided to maintain in operative position, helically
20 wound resistor members that are threaded into the grooves and extend longitudinally thereof.

In the single sheet of drawings,

Figure 1 is a top plan view of an electric heating unit employing my invention; and
30

Fig. 2 is a sectional view of the electric heating unit shown in Figure 1, taken along the line II-II of Figure 1.

A refractory electrical insulating member
35 11 supports terminals 12, 13, and 14 in a manner hereinafter more fully described. A pair of spiral grooves 15 and 16 are provided in the refractory member 11 and are so constructed that in a cross section taken
40 at right angles to a tangent thereof, the walls 17 and 18 of one groove, and 19 and 21 of the other groove are disposed angularly relatively to each other. Bridging members 22, that are integral with the plate
45 11, extend between the walls 17, 18, 19 and 21 laterally thereto and are disposed at suitable intervals along the grooves.

Resistor members 23 and 24 are located in the grooves 15 and 16, respectively, and are maintained in operative position therein by the bridging members 22. Bolts 25, 26 and 27 are provided to secure resistor members
50 23 and 24 at their ends thereof to the refractory member, and are connected by

conductors 28, 29 and 31 to terminal mem- 55 bers 12, 13 and 14. The refractory member 11 is perforated and countersunk at 32, 33 and 34 to provide a practical means for locating bolts 25, 26 and 27 in operative position. The refractory member 11 is also 60 perforated at 35, 36 and 37 to provide practical means for securing the heating unit to any supporting means not shown.

Terminal members 12, 13 and 14 are supported by a refractory member 38 of partially rectangular and partially arcuate shape that is secured to the refractory member 11 by bolts 39 and 41 extending therethrough.

In assembling the heating unit resistor 70 the members 23 and 24 are threaded through the grooves 15 and 16 and are secured to the refractory member 11 at their ends by the bolts 25, 26 and 27. The conductors 28, 29 and 31 are threaded through the terminal supporting member 38 and are connected to the resistor members 23 and 24 and maintained in operative relations therewith by the bolts 25, 26 and 27. The terminal supporting member 38 is secured to the 80 refractory member 11 by the bolts 39 and 41.

The diameter of the helix is made relatively large so that it will be located well above the bottom of the groove of V-
85 shape. The helically wound resistor member therefore operatively engages the side walls with a line contact only. The flow of heat by direct conduction from the wire to the refractory support is, therefore, reduced to a very small amount, and this 90 results in transmitting a larger percentage of the heat generated in the wire by direct radiation to material placed on or above the grooved supporting member 11. This results also, in a quicker heating up of the 95 unit. The hot spot, which usually is present immediately beneath the bottom portion of the wire helix when located in a groove having a rounded bottom, is entirely avoided.

This construction therefore permits of obtaining a quick initial heating, a reduced flow of heat downwardly and the avoidance of dangerous hot spots and, in general, the operation of this heating unit is very similar 105 to the operation of an open type of heating unit.

It is obvious that a structure embodying

my invention provides a simple, practical electric heating unit that is easily assembled and that may be readily disassembled to permit a renewal of resistor members.

5. Various modifications and changes may be made without departing from the spirit and scope of the invention, and I desire therefore that only such limitations shall be placed thereon as are imposed by the 10 prior art or are set forth in the appended claims.

I claim as my invention:

1. An electric heating unit comprising a helically wound resistor member, and a refractory electrically insulating member having grooves for supporting said resistor member, the walls of said grooves being so constructed as to maintain a line contact only with said resistor member.

20 2. In an electric heating unit, the combination with a refractory electrically insulating member having a grooved portion, of a helically wound resistor member supported by the walls only of said grooved 25 portion.

3. In an electric heating unit, the combination with a refractory electrically insulating member having a grooved portion whose section has non-parallel sides, of a 30 helically wound resistor member, supported in said grooved portion by the walls thereof.

4. In an electric heating unit, the combination with a refractory electrically insulating member having a grooved portion, 35 said grooved portion having longitudinally spaced bridging members extending laterally between the walls of said grooved portion, of a helically wound resistor member supported by the walls only of said grooved

portion, and maintained in operative position by said bridging members. 40

5. In an electric heating unit, the combination with a refractory electrically insulating member having a grooved portion, 45 said grooved portion having longitudinally spaced bridging members extending laterally between the walls of said grooved portion and having a cross section of non-parallel sides, of a helically wound resistor member supported in said grooved portion by the walls thereof and maintained in operative position by said bridging members. 50

6. In an electric heating unit, the combination with a refractory electrically insulating member having a grooved portion, 55 of a helically wound resistor member supported by the walls of said grooved portion and maintained in line contact only therewith. 60

7. In an electric heating unit, the combination with a refractory electrically insulating member having a grooved portion, 65 said grooved portion having longitudinally spaced bridging members extending laterally between the walls of said grooved portion and having a cross section of non-parallel sides, of a helically wound resistor member so supported in said grooved portions by the walls thereof as to maintain a line contact only with said walls, and maintained in operative position by said bridging members. 70

In testimony whereof, I have hereunto 75 subscribed my name this tenth day of April 1924.

ERNEST E. SUTHERLAND.
